US00D780063S

(12) **United States Design Patent** (10) **Patent No.:** **US D780,063 S**
(45) **Date of Patent:** **** Feb. 28, 2017**

(54) **AUTOMOTIVE VEHICLE EXTERIOR**

(71) Applicant: **McLaren Automotive Limited**,
Woking, Surrey (GB)

EM 000216650-0001 4/2005
EM 000681218-0002 3/2007

(72) Inventor: **Frank Stephenson**, Berkshire (GB)

(73) Assignee: **McLaren Automotive Limited**,
Woking (GB)

(**) Term: **15 Years**

(21) Appl. No.: **29/527,356**

(22) Filed: **May 18, 2015**

(30) **Foreign Application Priority Data**

Nov. 18, 2014 (GB) 4038226
(51) **LOC (10) Cl.** **12-08**
(52) **U.S. Cl.**
USPC **D12/88; D12/92**
(58) **Field of Classification Search**
USPC D12/86, 90-92, 88; D21/421, 433, 434;
296/181.1, 181.5
CPC B62D 35/00; B62D 25/00; B62D 25/06;
B62D 33/00
See application file for complete search history.

(57) **CLAIM**

The ornamental design for an automotive vehicle exterior.

DESCRIPTION

FIG. 1 is left side, front, top perspective view of an automotive vehicle exterior showing my new design;
FIG. 2 is a left side, rear, top perspective view thereof;
FIG. 3 is a front view thereof; and
FIG. 4 is a rear view thereof.

FIG. 5 is a right side elevation view thereof;
FIG. 6 is a left side elevation view thereof; and,
FIG. 7 is a top plan view thereof.

The invention is shown together with environmental structure in dashed lines in FIGS. 1-6, the environmental structure forming no part of the claimed design.
The broken lines shown throughout the drawing views are for illustrative purposes only and form no part of the claimed design.

1 Claim, 7 Drawing Sheets
